(57) **CLAIM**

I claim the ornamental design for a portable material separator, as shown and described.

DESCRIPTION

FIG. 1 is a perspective view of the portable material separator.

FIG. 2 is a side view of the portable material separator.

FIG. 3 is an opposite side view of the portable material separator.

FIG. 4 is another side view of the portable material separator.

FIG. 5 is a top view of the portable material separator.

FIG. 6 is a bottom view of the portable material separator; and,

FIG. 7 is a perspective view of the portable material separator with a bucket (illustrated by broken lines).

The broken lines shown in FIG. 7 depict a container (such as a bucket) utilized with the portable material separator and represent unclaimed subject matter and form no part of the claimed design.
